UNITED STATES PATENT OFFICE.

OSCAR M. LEICH, OF GENOA, ILLINOIS, ASSIGNOR TO LEICH ELECTRIC CO., OF GENOA, ILLINOIS, A CORPORATION OF ILLINOIS.

TELEPHONE RECEIVER.

Application filed June 2, 1922. Serial No. 565,406.

To all whom it may concern:

Be it known that I, OSCAR M. LEICH, a citizen of the United States, residing at Genoa, in the county of De Kalb and State 5 of Illinois, have invented a certain new and useful Improvement in Telephone Receivers, of which the following is a full, clear, concise, and exact description, reference being had to the accompanying drawings, forming 10 a part of this specification.

My invention relates to telephone receivers, and more particularly to a telephone receiver provided with a sheet metal cap. Telephone receivers have been frequently 15 made with a metal casing but are generally provided with a cap for closing the casing, which is made of vulcanite or hard rubber. In certain kinds of telephone work, such as radio work, it is desirable that the receiver or 20 receivers be made as light as possible, and in order to provide a light receiver I have dispensed with the vulcanite or hard rubber cap, which is comparatively heavy, and have provided a cap made of sheet metal, prefer- 25 ably sheet aluminum, which screw-threadedly engages the aluminum shell of a receiver, said cap being provided with an inwardly struck rib which engages with the diaphragm provided in the receiver to clamp 30 the edge thereof against the support on the inside of the receiver. The aluminum cap may be dipped in suitable paint which may in itself be an insulator, or if desired, the cap may be provided with a separate insu- 35 lating covering of comparatively thin rubber. While it is not ordinarily necessary to insulate the cover, yet if this is desired, the rubber covering may be provided on the metal cap.

40 Other objects and advantages of the invention will appear as the description of the accompanying drawings proceeds. However, I desire to have it distinctly understood that I do not intend to limit myself to the 45 exact details shown or described, but that I intend to include as part of my invention all such obvious changes and modifications of parts as would occur to a person skilled in

this art, and as would fall within the scope of the claims.

In the drawings:

Fig. 1 is a face view of my improved receiver viewed from the cap end thereof;

Fig. 2 is a view in side elevation of the receiver showing the cap in cross section, 55 being taken on the line 2—2 of Fig. 1; and

Fig. 3 is a similar view showing the rubber covering on the cap.

Referring in detail to the drawings, a receiver is shown comprising a metal shell 5 which is preferably stamped out of sheet aluminum, and which is provided with screw threads at 6 for screw-threadedly receiving the sheet metal cap 7, said cap being also preferably made of aluminum and being provided with the screw threads at 8 engaging with the screw threads 6. The cap 7 is provided with a central opening 9 as is customary, and is provided with an inwardly struck annular rib 10 which engages with the diaphragm 11 holding the same against its support 12. By striking the rib 10 inwardly, an exterior annular groove 13 is provided opposite the rib 10, as the material of the cap is provided with an outwardly extending fold 14 which merges into the flange 15 having the threads 8 thereon. If desired, the cap 7 may be provided with a rubber covering 16 which is provided with a flange portion 17 embracing the flange 15, said flange 17 being shaped to conform substantially to the contour of the outer surface of the cap 7 adjacent the flange, and due to the fact that the portion 14 is of larger radius than the flange 15, the rubber covering 16 will be held firmly in position by means of the flange 17. In order to aid in holding the cover 16 in position, an enlargement or bead is provided at 18 which is annular, and is adapted to seat in the exterior groove 13 to hold the rubber covering in position. The covering 16 is also provided with an enlargement or bead at 19 extending around the opening 20 therein corresponding to the opening 9 in 95 the cap 7 so as to strengthen or stiffen the

material of the rubber covering at said opening.

Having thus described my invention, what I desire to claim and secure by U. S. Letters Patent is:

1. In a telephone receiver, a metal shell, a metal cap and a rubber cover member for said cap, said cap having a bead thereon around which said cover member extends to hold said cover in position and said cover member having an annular rib thereon

adapted to seat in a corresponding groove in said cap.

2. In a telephone receiver, a metal shell, a metal cap and a rubber cover member for said cap, said cap and cover having aligning openings and said cover being thickened at said opening.

In witness whereof, I hereunto subscribe my name this 12th day of May, A. D., 1922.

OSCAR M. LEICH.
